A. B. Upham,
attorney.

UNITED STATES PATENT OFFICE.

RICHARD GREENLEAF TURNER, OF MALDEN, MASSACHUSETTS.

WOVEN FABRIC.

1,320,996.

Specification of Letters Patent.

Patented Nov. 4, 1919.

Application filed January 14, 1918. Serial No. 211,747.

To all whom it may concern:

Be it known that I, RICHARD GREENLEAF TURNER, a citizen of the United States, and a resident of the city of Malden, in the 5 county of Middlesex and Commonwealth of Massachusetts, have invented certain new and useful Improvements in Woven Fabrics, of which the following is a full, clear, and exact specification.

10 In an application filed by me June 12, 1917, Serial No. 174,233, for improvements in looms, I disclose means whereby the weft thread is fed through a vertical tube to the interior of the shed, passing therefrom 15 into the control of the shuttle. Four harness frames are employed, two for the warp threads of one lateral half of the fabric, and the other for the warp of the other half.

In this present application is disclosed 20 and claimed the peculiar type of fabric which is produced by the loom. The main novelty of this fabric is that every shed contains two weft threads, and yet these two are both sections of the same thread. This 25 multiplication of the weft or filler in each warp shed is accomplished by doubling upon itself a section of weft thread equal in length to the width of the fabric, and uniting these contacting halves in the same sheds, the 30 lower half of each doubled length being continuous with the upper half of the next doublet at the other side of the fabric.

In other words, the weft threads are in 35 pairs doubled at the selvage edge of the fabric, each leg of each pair merging into a leg of another pair in the other lateral half of the fabric, the two legs of each pair being confined in the same warp sheds.

In the drawings forming part of this 40 specification, Figure 1 is a plan view, partly in section and diagrammatic, of a loom upon which the fabric can be woven. Fig. 2 is a side sectional view of the same. Fig. 3 is a face view of a length of the fabric embodying 45 my improvement, the threads being illustrated as widely separated. Fig. 4 is a plan view of an elemental portion of the weft.

In the loom, the weft thread 1 is received 50 from any suitable source and delivered to the upper end of a vertical tube 3 terminating at its lower end in a horizontal elbow 4. This elbow is given a periodic oscillation to and from the position shown in 55 Fig. 1 to and from a similar one at the right

of the center line of the loom, for the purpose hereinafter described.

At each side of the shed is a shuttle box 60 11 and a picker stick 13 for the actuation of the shuttle 12.

The warp threads are in four sets, the set 21 passing through heddles 22 carried by a harness frame 23; the set 24 passing through heddles 25 carried by the harness frame 26; the set 27 passing through heddles 29 carried by a harness frame 30, and a set 28 passing through heddles 31 carried by a harness frame 32; all the warp threads being drawn over the breast-beam 33 and fastened to the cloth beam 34 in the usual manner. 70

Immediately preceding a blow of a picker stick 13 by which the shuttle 12 is shot through the shed to the opposite shuttle box 11, the arm 4 is turned to a position between the warp threads connected with the farther half of the breast-beam 33; and, the weft thread 1 running freely in an eye in the shuttle and through the tube 3 and arm 4, the shuttle deposits a length of weft the 80 entire width of the sheds. As soon as the shuttle has thus passed, the shuttle and arm being now in the positions illustrated in Fig. 1, the harness frames 26 and 32 reverse their position to lower the warp 24 and raise the 85 warp 27. Immediately following this, a beater comb 35 acts to press the weft firmly in place, and then the arm 4 swings toward the right and the shuttle 12 is thrown across; the harness frames 23 and 30 are reversed; the beater comb again swings forward and returns; again the shuttle and arm move over, and so on indefinitely. 90

Thus operated, the loom will weave the 95 fabric shown in Fig. 3, wherein it will be seen that every shed contains two strands of weft but that the two strands in one lateral half of the fabric are not both coterminous with those in the other half. Or, as otherwise described, a weft element comprises 100 four parallel thread-sections each equal to half the width of the fabric, the sections 1^a and 1^b being almost in alinement and united by a slight offset 1^c; the sections 1^d and 1^e being united to the ends of the 105 elements 1^a, 1^b by bends 1^f at the edges of the fabric, but at opposite sides of the sections 1^a, 1^b. The sections 1^a, 1^d are confined together in the sheds 40, and the sections 1^b, 1^e are confined together in the 110

sheds 41, the line of sheds 40 being not quite in alinement with the line of sheds 41. The section 1^a of one weft element is united by a slight offset 1^s to the end of the section 1^e of the next weft element.

5 Each weft element may be likened to a letter S turned on its side and pressed flat, the ends of each element merging into the ends of those adjacent thereto.

10 By having the fabric thus made, the loom producing the same can be run indefinitely without stop or delay for the supply of fresh spools of weft thread, since the latter can be taken direct to the loom from any 15 suitable external reel of any desired capacity. Not only does this save much time and labor in the process of weaving, but even more in the labor and other expenses associated with winding the bobbins. It 20 has been conservatively estimated that for medium sizes of jute and burlap, there is a total saving in expense for labor, power, interest and general overhead, of not less than twenty-five per cent.; and for heavier 25 sizes, an even larger saving.

It might be thought that, since there is no warp thread passing within the bends or loops 1^f, the weft threads will not hold the warp along the selvage edges of the 30 fabric, and to guard against the same I provided the loom set forth in my said companion application with stitching devices for binding together, and to the outermost warp threads, said loops 1^f. In actual 35 practice, however, I do not find this uniformly necessary, although in some grades of fabric and some uses, it is desirable. For the latter I provide, either in the manner illustrated in said companion application, or otherwise, an extra thread 42 shown 40 at the right hand edge of the fabric in Fig. 3, adapted by its engagement with the loops or bends 1^f to lock the outermost warp threads from pulling out from their engagement with the weft threads.

45 It should be noted that in this fabric the warp is centrally divided by an imaginary line, which separates the transverse lines of sheds at one side from the lines at the other 50 side, the sheds at each side of the line being staggered with respect to those at the other side. In other words, the sheds next to said

line alternate in longitudinal position with the sheds next to the other side of this line.

What I claim is:

1. A woven fabric having warp and weft threads, every warp shed containing two strands of weft, one of which strands is continuous and parallel with one of the strands in another lateral section of the fabric but 60 slightly out of alinement therewith, each lateral section of weft thread being united to its other lateral section by an oblique offset, and every alternate oblique offset being 65 parallel.

2. A woven fabric having warp and weft threads, each warp shed containing two strands of weft doubled together with the loop in the selvage of the fabric and their ends continuous with the ends of like folded 70 strands in the other lateral half of the fabric, each lateral half of a weft thread being integral with another lateral half through an oblique offset, every alternate oblique offset being parallel.

3. A woven fabric having warp and weft threads, every warp shed containing a pair of weft-sections, each pair extending substantially half the width of the fabric and 80 consisting of a length of thread doubled over on itself, the loop lying in the edge of the fabric, the weft-sections being all parallel and one end of each pair being continuous with an end of the pair adjoining in the opposite lateral half of the fabric, the 85 sheds in one lateral half of the fabric being slightly out of alinement with the sheds in the other lateral half.

4. A woven fabric having warp and weft threads, every warp shed containing two 90 strands of weft doubled together with the loop in the edge of the fabric and their ends continuous with the ends of like folded strands in the other lateral half of the fabric, each lateral half of a weft thread being 95 united to its other lateral half by an oblique offset, every alternate oblique offset being parallel, and a thread passed longitudinally of the fabric through the loops at each edge thereof.

In testimony that I claim the foregoing invention, I have hereunto set my hand this 100 11th day of January, 1918.

RICHARD GREENLEAF TURNER.
